UNITED STATES PATENT OFFICE.

EDWARD C. CURSONS, OF BUFFALO, NEW YORK.

CASHIER'S BOX.

Application filed August 7, 1925. Serial No. 48,778.

This invention relates to a money box for use by cashiers of electric light, gas and other companies whose customers usually pay their bills in groups at certain times each month, which payments in many instances are made in paper money of small denominations, such as one, two, five and ten dollar bank notes. During the rush hours money of this character makes unwieldy piles which the cashier, in many instances, is unable to dispose of conveniently, especially as this paper money is frequently badly wrinkled. This not only causes delay in making change but also unnecessarily prolongs the time in getting the paper money ready for banking inasmuch as the paper money has to be smoothed out before it can be strapped or put up in bundles or packages ready for banking.

The purpose of this invention is to provide a money box which will enable a cashier to conveniently pile the paper money as the same is received and to smooth the same so that subsequent handling for removing wrinkles is not required preparatory to bundling the money, also to permit the cashier to readily make change, to quickly dispose of part of the pile of paper money so that the pile will not be excessive in height and also avoid displaying an undue amount of money which otherwise might be a temptation for a hold-up, and also to so store the money that the same is safe and under the control of the cashier.

With this end in view this invention consists generally in providing one or more upper compartments in which the cashier is adapted to deposit the money in piles, one or more lower compartments each adapted to receive the excess of the pile of money in one of the upper compartments, and a spring pressed partition arranged between each upper compartment and a companion lower compartment and adapted to be deflected by the hand pressure of the cashier for causing more or less of the stack of money in each upper compartment to be discharged into the form of a pile in the respective lower compartment and stored there ready to be subsequently removed for counting and bundling preparatory to being carried to the bank.

In the accompanying drawings:—

Figure 1 is a perspective view showing my improved money box mounted in the form

of a drawer in the pocket or runway of a cabinet or desk.

Figure 2 is a similar view showing the money box wholly removed from the cabinet.

Figure 3 is a vertical longitudinal section of the money box taken on line 3—3, Fig. 2.

Fig. 4 is a vertical cross section taken on line 4—4, Fig. 2 looking forward.

Figure 5 is a fragmentary top plan view 65 of the money box shown in Figures 1—4.

Figure 6 is a perspective view of one form of rack for movably supporting the money box in the pocket of a cabinet.

Figure 7 is a top plan view of a money 70 box having a plurality of compartments arranged in a transverse row and provided with an arrangement of partitions differing from that shown in Figures 3 and 4.

Figures 8 and 9 are top plan views showing further modifications in the manner of constructing and mounting the partitions.

Figure 10 is a fragmentary vertical section, on an enlarged scale, of a spring hinge 80 for pivotally and yieldingly mounting a partition between an upper and a lower compartment of the money box, the section being taken on line 10—10, Fig. 4.

Similar characters of reference indicate like parts in the several figures of the drawings:—

The money box proper may be organized so as to embody one or more units of upper and lower compartments which are superposed in pairs, the particular embodiment of the invention illustrated in the drawings, Figures 1—3, containing four of such units.

Each of these units comprises an upper compartment 10 into which the cashier places the paper money or bank notes 95 through the normally open top of this compartment, and a lower compartment 11 arranged below the respective upper compartment and adapted to receive the money from the latter. The upper compartment is shallower than the lower compartment and preferably about one third the depth of the latter inasmuch as the upper compartment is intended to hold only a comparatively low stack of bills while the lower compartment 105 is intended to receive and store a comparatively high stack of bills or bank notes.

The upper and lower compartments of the pair of each unit are separated by a partition or shelf 12 which is normally arranged 110

in a horizontal position and serves as a shelf for supporting the pile of bills in the upper compartment and which is capable of being deflected downwardly by hand pressure of the cashier for discharging all or some of the pile of bills on the shelf downwardly so as to form a pile which rests on the bottom of the lower compartment.

Various means may be provided for movably supporting each partition or shelf and yieldingly holding the same in an elevated horizontal position. The means for example, shown in Figures 3, 4 and 10, consist of a spring hinge having its front leaf 13, connected with the underside of a horizontal flange 14 on the inner side of the upper part of the front wall 15 of the money box and its rear leaf 16 connected with the underside of the front end of the partition or shelf 12, said leaves being provided with depending ears 17, 18 which are pivoted together by a horizontal transverse pintle 19. The partition is yieldingly held in its normal horizontal or uppermost position by a spring 20 surrounding the pintle and bearing at its ends against the underside of the flange 14 and the underside of the partition. The upward movement of the partition under the action of said spring is arrested when the partition is in a horizontal position by engagement of the front edge of the partition 12 with the rear edge of the flange 14, which cooperating edges form stops for this purpose.

As the cashier receives a paper bank note in payment of an account this paper bill is placed flatwise on top of the partition forming the bottom of one of the upper compartments or upon bills of the same denomination previously deposited in this compartment. When the height of the pile of bills in the upper compartment has nearly reached the top of the latter, or at any other time if desired, the cashier may reduce this height by pressing the pile downwardly together with the partition so that the position of the latter is shifted from the horizontal position shown by full lines in Figure 3, to the rearwardly inclined position shown by dotted lines in the same figure, and at the same time the cashier pushes all or some of the bills from the upper side of the partition downwardly between the rear edge of the latter and the rear wall of the box into the companion lower compartment. As the bills enter the latter they stack themselves flatwise on the bottom of the lower compartment, or on the bills previously deposited therein, whereby the bills are smoothed or have their wrinkles removed sufficiently to permit of subsequently strapping the paper money in bundles without requiring the same to be straightened out and smoothed for this purpose, thereby facilitating handling the money and getting the same

ready for banking. As soon as the pressure of the hand is removed from the partition or the pile of money resting thereon this partition is automatically raised into its normal horizontal or upper position ready to receive additional bills from the cashier. A few bills of different denominations are preferably kept in reserve in each of the several upper compartments in order to enable the cashier to make change if this becomes necessary.

If the rear edge 9 of the partition is arranged close to the rear wall 21 of the upper and lower compartments the cashier when passing his hand with the bills downwardly from the upper to the lower compartment is liable to get his hand caught between the partition and said rear wall and while no injury would result the experience might be unpleasant and cause fright and possible dislike of this money box. To avoid such a contingency the rear edge 9 of the partition stops short and is separated from the adjacent surface or rear wall 21 by an intervening space or gap 8 which is sufficiently wide to permit a considerable part of the hand to be passed therethrough without becoming caught but still leaving enough partition or shelf area to properly support a pile of bills in the upper compartment.

In order to take care of occasional bills of large denominations, such as twenty, fifty, or hundred dollar bills, two supplemental compartments 22 and 23 are provided which are arranged in rear of the upper compartments and preferably of the same depth but not associated with any lower compartments inasmuch as the stack of such bills, as a rule, does not become very high.

For the purpose of enabling the piles of bills to be conveniently removed from the several lower compartments a movable door 24 is provided which forms the front walls of the several lower compartments and which in the preferred construction is pivotally connected at its lower end by a pivot or hinge 25 having its axis arranged horizontally and transversely of the box while its upper end is adapted to be fastened to the body of the box by means of a lock 26 of any suitable construction.

When the money box is in use the tops of the upper compartments and the supplemental compartments are uncovered but when the same contains a lot of cash and is not used by the cashier the tops of the upper compartments and the supplemental compartments are closed by a movable cover 27 which is preferably pivotally connected at its rear edge with the upper rear corner of the money box by a hinge 28 having its axis arranged horizontally and transversely and its front edge is adapted to be secured to the upper front corner of the box by a lock 29 of any suitable construction. When

the money box is thus locked at the front and at the top, as shown in Figure 3, the same together with its contents may be transported from the cashier's desk or cabinet and stowed away in a vault or other place for safe keeping until the same is again required or to await the most opportune time for counting and strapping the money. When the cover is not in use the same hangs downwardly along the rear side of the box, as shown in Figure 2.

Although this box may be mounted in any suitable manner for use by the cashier it is preferable to provide the cashier's desk or cabinet 30 on its rear side with a pocket or runway 31 into and out of which the money box may be moved in the manner of a cash drawer or till, as shown in Fig. 1.

This box may be secured either in its outer or inner position relatively to the pocket in the cabinet by a lock 32 on the cabinet cooperating either with an outer lock opening 33 or an inner lock opening 34 in the adjacent side wall of the box.

For easily moving the box into and out of the cabinet pocket a carriage or rack 35 is provided which supports the box on its under side and has rollers 36 which run on tracks 37 on opposite sides of the pocket.

Instead of pivotally mounting the partitions on the front walls of the upper and lower compartments the partitions 38 may be mounted on the rear walls of these compartments, as shown at 39 in Fig. 7.

If desired the partition 40 may be pivotally mounted at one of its longitudinal edges on the adjacent longitudinal wall of the respective compartment by means of a hinge 41 having its axis arranged lengthwise and horizontally, as shown in Fig. 9.

Another way in which the partition may be constructed is shown in Fig. 8 in which the partition is divided into front and rear sections 42, 43, which are connected at their front and rear edges with the adjacent parts of the box walls by spring hinges 44, 45, and have their opposing edges separated by an intervening space or gap 46, so as to prevent the hand of the cashier from being cut, pinched, or otherwise injured.

I claim as my invention:

1. A cashier's box comprising an upper compartment, a lower compartment arranged below the upper compartment, and a movable partition arranged between the upper and lower compartments and adapted to support the money in the upper compartment and to be deflected downwardly by hand pressure against said partition to permit the passage of money from the upper to the lower compartment, said upper compartment permitting money to be deposited and removed therefrom manually at will from the top of this compartment.

2. A cashier's box comprising an upper

compartment, a lower compartment arranged below the upper compartment, a movable partition arranged between the upper and lower compartments and adapted to support the money in the upper compartment and to be deflected downwardly by hand pressure against said partition to permit the passage of money from the upper to the lower compartment, and means for yieldingly holding the partition in its normal position in which it separates the upper and lower compartments, said upper compartment permitting money to be deposited and removed therefrom manually at will from the top of this compartment. 70

separated from the opposing surface by an intervening gap said upper compartment permitting money to be deposited and removed therefrom manually at will from the 5 top of this compartment.

6. A cashier's box comprising an upper compartment, a lower compartment arranged below the upper compartment and adapted to receive money therefrom, a partition adapted normally to be arranged in 10 a horizontal position between said compartments and pivotally connected at one edge

with the box to turn about a horizontal axis and having its opposite edge normally separated from the opposing surface by an intervening gap, a spring for yieldingly holding said partition in an elevated position, and a stop for limiting the upward movement of said partition said upper compartment permitting money to be deposited and removed therefrom manually at will from the 15 20 top of this compartment.

In testimony whereof I affix my signature.
EDWARD C. CURSONS.
